[57] CLAIM

The ornamental design for a golf grip alignment training device, as shown and described.

DESCRIPTION

FIG. 1 is a top plan view of a golf grip alignment training device showing our new design;

FIG. 2 is a bottom plan view thereof;

FIG. 3 is a left side elevational view thereof;

FIG. 4 is a right side elevational view thereof;

FIG. 5 is a rear elevational view thereof;

FIG. 6 is a front elevational view thereof; and,

FIG. 7 is a top front right side perspective view thereof, to a larger scale than FIGS. 1–6.

The phantom lines in FIG. 7 represent the handle of a golf club and are not part of the claimed design.
